UNITED STATES PATENT OFFICE.

EDWARD L. KASTLER, OF FAIRMONT, MINNESOTA, ASSIGNEE TO FAIRMONT RAILWAY MOTORS, INC., OF FAIRMONT, MINNESOTA, A CORPORATION OF MINNESOTA.

CAR FRAME.

Application filed June 15, 1925. Serial No. 37,263.

This invention relates to improvements in car frames particularly designed for use in the construction of railway motor cars or hand cars, and more particularly relates to the particular method of constructing such a car frame.

An object of this invention is to provide a car frame of the above mentioned type comprising a pair of side beams suitably secured together to provide a frame which will be comparatively light in weight and having means thereon for resisting torsional strain in the frame, as when lifting the car from and onto the rails.

A further object of the invention is to provide a car frame having the side beams thereof connected together by a plurality of cross beams and said cross beams being suitably braced by means of diagonal braces so arranged as to minimize horizontal and vertical frame distortion, and also by means of which the lateral cross members of the frame will be held against rolling action caused by the inertia or momentum of the load carried thereon, when the car is subjected to a shock from a collision or sudden application of the brakes.

The particular object of the invention, therefore, is to provide an improved car frame of simple and inexpensive construction which will be strong and durable, and will be comparatively light in weight so that it may readily be lifted from and onto the rails as is customary in devices of this kind.

Other objects of the invention will appear from the following description and the accompanying drawings and will be pointed out in the annexed claims.

In the drawings there has been disclosed a structure designed to carry out the various objects of the invention but it is to be understood that the invention is not confined to the exact features shown as various changes may be made within the scope of the claims which follow.

In the accompanying drawings forming part of this specification,

Figure 1 is a plan view of the improved car frame;

Figure 2 is a side elevation of Figure 1; and

Figure 3 is a cross sectional view on the line 3-3 of Figure 1.

The novel car frame featured in this invention preferably comprises the opposed side beams or sills 4 which are mounted upon cross beams 5 as shown in the drawings. The cross beams 5 are suitably mounted upon and secured to the bearing brackets or 55 housings 6 in which the axles 7 are rotatably mounted, as is customary in structures of this type. The usual carrying wheels 8 are terminally mounted upon the axles 7. Referring to Figures 1 and 2, it will be noted 60 that the cross beams 5 are arranged in pairs and have their ends secured to the bearing brackets 6, thereby providing in effect two 65 rectangular truck frames which are connected together by means of the opposed sills 4 and a plurality of diagonal braces which 70 will subsequently be described.

An important feature of this invention resides in the novel means provided for securing together the two truck frames composed of the cross beams 5. Such means preferably consists in securing a pair of diagonal braces 9 to the upper edges of the cross beams 5 and a pair of similar diagonal braces 10 to the lower edges thereof. These 75 diagonal braces are riveted or bolted together at the point where they intersect one another, by means of a rivet or bolt 11, as particularly shown in Figure 3. The rivet or stud 11 may be provided with a shoulder 80 at each end thereof so that when the opposed ends are inserted through the apertures provided in the braces, and are headed over, as shown, the upper and lower braces 85 of the frame will be spaced apart as shown 85 in Figure 3. Suitable bolts or screws 12 are provided for securing the diagonal braces 9 and 10 to the cross beams 5.

When the two truck frames, composed of the cross beams 5 and the bearing brackets 95 or housings 6, are thus secured together by means of the diagonal braces 9 and 10, and the longitudinal side beams or sills 4 are mounted thereon as shown; a very rigid and rugged frame structure will be provided. 100 Also as a result of the diagonal braces 9 and 10 being thus arranged in pairs and a pair of such braces being secured to the upper and one to the lower edges of the cross beams 5, the frame when completed will be greatly 105 strengthened. This increased strength in the construction of the car frame is obtained by the spaced relation of the diagonal braces

and as a result of connecting them together at their intersections by the rivet 11, as previously described. By such spacing of the diagonal braces, any tendency to raise one of the wheels from the rails will exert a tensional strain upon one of the diagonal braces 10 at the bottom of the frame, while one of the upper braces 9 will be put under compression. Conversely, when one of the wheels has been lifted from the rail and lowered to a point beneath the surface of the rail or out of contact with the ground, a tensional strain will be exerted on one of the upper braces 9 while the complementary lower brace will be put under compression. It will, therefore, readily be seen and understood that by this novel arrangement of the diagonal braces 9 and 10, the frame will be greatly strengthened and at the same time its weight will be reduced to a minimum. Also by thus securing together the cross beams 5 by means of the spaced diagonal braces 9 and 10 and the sills 4, the car frame, when completed, will be practically free from horizontal and vertical diagonal frame distortion. Considerable stiffness and rigidity will also be added to the frame with a minimum amount of material, thereby providing a frame structure which is well adapted for use in the construction of railway motor and hand cars.

When it is desired to mount an engine on the frame as in the case of a motor driven car, additional frame members 13 may be mounted upon the cross beams 5 to support the engine. In the structure here shown, a lift rod or bar 14 is arranged at each end of the car frame to provide means for lifting the car from and onto the rails. A draw bar 15 is also shown at each end of the car frame having their inwardly extending ends secured to the adjacent cross beams 5 while their outer end portions may be secured to the lift rods 14 by means of U-bolts 16. An auxiliary cross beam 17 may also be provided adjacent each end of the frame to provide an additional supporting means for the draw bars 15, as shown in Figures 1 and 2. These auxiliary cross beams are preferably secured to the side beams or sills 4.

I claim as my invention:

1. A railway car comprising truck frames and brace bars arranged diagonally of said truck frames above and below them and in

crossed relation and secured to said truck frames.

2. A railway car comprising truck frames having cross beams arranged in pairs and side sills connecting the pairs of cross beams and extending transversely thereof, and brace bars arranged in crossed relation diagonally of said truck frames and secured to the cross beams of said truck frames and to said side sills.

3. A railway car comprising truck frames, side sills mounted on said frames, and brace bars arranged diagonally of said truck frames above and below them and in crossed relation and secured to said truck frames and to said side sills.

4. A railway car comprising truck frames, side sills mounted on said frames, brace bars arranged in pairs above and below said truck frames and extending diagonally thereof and having their end portions secured to said truck frames and to said side sills.

5. A railway car comprising truck frames, side sills mounted on said frames, brace bars arranged in pairs above and below said truck frames and extending diagonally thereof and having their end portions secured to said truck frames and to said side sills, the middle portions of said brace bars having means for securing the upper and lower pairs together at their points of intersection.

6. A railway car comprising truck frames, side sills mounted on said frames, brace bars arranged in pairs above and below said truck frames and extending diagonally thereof, and having their end portions secured to said truck frames, and a bolt passing through the bars of said pairs at their points of intersection and securing them together, said brace bars preventing horizontal and vertical distortion of said car frame.

7. A railway car comprising truck frames in spaced parallel relation, side sills mounted on said frames and means extending transversely of said car and diagonally thereof and secured to the upper and lower portions of said truck frames for resisting vertical and horizontal torsional strains thereon.

In witness whereof, I have hereunto set my hand this 11th day of June, 1925.

EDWARD L. KASTLER.
